UNITED STATES PATENT OFFICE.

EDMUND W. DONOVAN, OF DETROIT, MICHIGAN.

DESIGN FOR MEMENTOES FOR PERPETUATING THE MEMORY OF DECEASED FRIENDS AND RELATIVES.

SPECIFICATION forming part of Design No. 11,756, dated April 27, 1880.

Application filed January 21, 1880. Term of patent 7 years.

To all whom it may concern:

Be it known that I, EDMUND W. DONOVAN, of Detroit, in the county of Wayne and State of Michigan, have invented a new and useful 5 Design for Mementoes for Perpetuating the Memory of Deceased Friends and Relatives; and I do hereby declare that the following is a full, clear, and exact description of the same, reference being had to the accompanying fac- 10 simile, forming part of this specification.

My design consists of ornamental configurations printed in gilt upon a dark or black card-board or paper, which may be subsequently suitably mounted, which, in size, is 15 about eight by ten inches.

The gilt configurations consist of a border having floral sides, ends, and corner-pieces, within which are printed, at the top, the words "Sacred to the Memory of," at each end bor- 20 dered spaces for the insertion of the picture of the deceased, and a suitable poem at the center, and near the bottom rectangular spaces having ornamental borders for the reception of the name, age, and the date of the person's death. The bordered spaces within the surrounding border are intended to be cut out for the purpose of inserting the appropriate memorial, and the card-board, after receiving them, is to be suitably framed for preservation and exhibition.

Having thus fully described my invention, what I claim is—

The design for a memento herein described, consisting of a dark or black card-board, on which is printed in gilt a surrounding floral border, within which are printed borders forming spaces for the reception of pictures of the deceased person commemorated, poems, name, age, and date of death of the person, as set forth.

In testimony that I claim the foregoing as my own I affix my signature in presence of two witnesses.

EDMUND W. DONOVAN.
